(57) **CLAIM**

The ornamental design for a caddy, as shown and described.

DESCRIPTION

In a preferred embodiment, the nature of this product is a caddy for carrying items such as food and/or drink, for example, a bottle of wine.

FIG. 1 is a right, top, front perspective view of a caddy according to our new design;

FIG. 2 is a front elevational view thereof, the rear elevational view thereof being a mirror image of the front view shown; FIG. 3 is a right side elevational view thereof, the left side elevational view thereof being a mirror image of the right side shown;

FIG. 4 is a top plan view thereof; and,

FIG. 5 is a bottom plan view thereof.

The broken line showing of fasteners in FIGS. 1, 4, and 5 is for illustrative purposes only and forms no part of the claimed design.
